UNITED STATES PATENT OFFICE

2,611,502

APERTURED EARS ON RECESSED LAMP FOR RECEIVING SUPPORTING RODS

Ivan M. Kirlin, Detroit, Mich., assignor to The Kirlin Company, Detroit, Mich., a partnership

Application January 25, 1950, Serial No. 140,419

3 Claims. (Cl. 220—3.92)

1

This invention relates generally to boxlike members which are particularly adapted, among other uses, for recessed light fixtures for insertion in buildings.

An object of this invention is to provide a new and improved recessed lighting fixture.

Another object of this invention is to provide an improved means whereby said recessed lighting fixture may be quickly and economically secured to a building.

Another object is to provide such a light fixture which may be placed in any of a variety of positions.

Another object is to provide a recessed-type lighting fixture with apertured ears whereby elongated rodlike members extending through said apertured ears and secured at opposite ends to opposite wall supporting elements support the fixture within a building wall or the like.

Other objects of this invention will be apparent from the specification, the appended claims, and the drawings in which drawings:

Figure 1 is a perspective view of a lighting fixture secured between two building joists or elements and illustrating the invention;

Fig. 2 is a view taken substantially along the line 2—2 of Fig. 1;

Fig. 3 is a sectional view of a building portion showing the fixture installed therein;

Fig. 4 is a view similar to Fig. 3 but showing the fixture supported in the building portion in a second adjusted position; and

Figs. 5 and 6 illustrate different positions of the tabs for supporting the fixture in different rotative positions.

Referring to the drawings by characters of reference, the numeral 1 indicates generally a recessed-type lighting fixture having a bottom wall 2, side walls 3 and 4 and end walls 5 and 6. The walls 2, 3 and 4 may be made from a single piece of sheet material such as sheet steel by bending to provide the corners 7 and 8. The end walls 5 and 6 are similar and have tabs or flanges 9, 10 and 11 which for the most part lie along the adjacent one of the walls 2, 3 and 4 and may be secured thereto as by weld spots 12. The tabs 10 and 11 have portions 13 which are provided with a plurality of spaced apertures 14. The apertures 14 in the various portions 13 are preferably equally spaced to provide aligned openings for receiving elongated rodlike supporting members 15 which extend between and are fastened to two adjacent structure supporting elements 16. It will be appreciated that such elements 16 may be wall studs or ceiling joists

2

depending upon where the fixture is to be installed. These rods 15 may be secured to the structure elements 16 by any suitable means, such as staples or screws 18. Subsequent to the installation of the recess lighting fixture 1 between the elements 16, the exterior wall trim, which may be lath 20 and plaster 22, may be applied.

The apertures 14 in the tabs 13 are spaced rearwardly from the front edge 24 of the fixture such that the front edge 24 of the lighting fixture may extend outwardly of the supporting elements sufficiently to permit the lath and plaster 20 and 22 or other finishing surface to be applied and the front edge 24 will be in substantial alignment with the finished wall, ceiling or other surface. The tabs 13 are bendable so that bars thereof may extend outwardly from the walls 3 and 4 when it is desired to support the recessed fixture 1 with the end walls 5 and 6 substantially parallel to the structural elements 16. When it is desired to support the recessed fixture 1 in a rotated position in which the walls 5 and 6 extend substantially laterally of the supporting elements 16, the tabs 13 may be bent to extend outwardly from the end walls 5 and 6. In this case the rods 15, instead of extending substantially parallel to the walls 3 and 4, will extend substantially parallel to the end walls 5 and 6, as shown in Fig. 6. After installation, the tabs 13 may be angularly bent in the direction of the support bars or rods 15 or deformed in a direction normal thereto to anchor the recessed fixture 1 in an adjusted position on the bars 15 between adjacent ones of the elements 16. The usual cover 30 may be applied in the usual manner.

I am aware that recessed fixtures have been used in the prior art but these fixtures required supporting brackets or similar elements for attaching them to the structural elements 16. With my apertured tabs, the recessed fixtures may be adjustably secured by the structural elements 16 having a wide difference in spacing and in which the recessed fixture may be spaced in any position between the two adjacent structural elements and which may be held in adjusted position by a simple bending of the perforated tabs through which the elongated members extend. Furthermore, by bending these tabs to extend outwardly from different walls, the fixture may be attached in its desired rotative position. By placing the rods in various sets of apertures, the front edge of the fixture may be made to substantially align between a wide variety of thickness of different finished surfaces.

What is claimed and is desired to be secured by United States Letters Patent is as follows:

1. A lighting fixture of the recessed type including, in combination, a box made of sheet material having four side walls and an end wall, a side wall at each corner having a flange overlapping the adjacent portion of the other side wall of each corner, said flange having a portion severed therefrom interjacent the ends thereof to form a tab leaving opposite end portions which are secured to the adjacent side wall portions, said tabs having at least one aperture therethrough spaced from the corner to permit a rod to extend along either side wall of a corner when disposed in the apertures in the tabs at the ends of said side wall in either position of alignment of the tabs with one or the other side wall at the corners.

2. A lighting fixture of the recessed type including, in combination, a box made of sheet material having four side walls and an end wall, a side wall at each corner having a flange overlapping the adjacent portion of the other side wall of each corner, said flange having a portion severed therefrom interjacent the ends thereof to form a tab leaving opposite end portions which are secured to the adjacent side wall portions, said tabs being bendable from a position of align-

ment with the secured end portions of the flange into a position of alignment with either side wall at the respective corner, and at least one aperture in each said tab spaced from the corner at which the tab is located.

3. A lighting fixture of the recessed type including, in combination, a box made of sheet material having four side walls and an end wall, a side wall at each corner having spaced flange portions overlapping the adjacent portion of the other side wall of each corner and secured thereto, one of said side walls of each corner having a tab located between said flange portions which may be bent to extend in alignment with either side wall of the corner, said tabs having apertures therethrough which are spaced from the corner at which the tab is located.
